[57] CLAIM

The ornamental design for a paraplegic's tricycle, as shown and described.

DESCRIPTION

FIG. 1 is a top and front perspective view of a paraplegic's tricycle showing my new design;

FIG. 2 is a rear and top perspective view of a second embodiment of the paraplegic's tricycle; the sole difference being in the alternate hand propulsion lever from that of FIG. 1;

FIG. 3 is a top plan view of the tricycle of FIG. 2;

FIG. 4 is a side elevational view of the tricycle of FIG. 2;

FIG. 5 is a front elevational view of the tricycle of FIG. 2;

FIG. 6 is a perspective detailed view of the alternate hand propulsion lever with the handles in a different position, the remainder of the tricycle being omitted for convenience of illustration; and,

FIG. 7 is a bottom plan view of the tricycle shown in FIG. 2.
